UNITED STATES PATENT OFFICE.

ALEXANDER GERLACH, OF LAUTERBACH, GERMANY, ASSIGNOR, BY MESNE ASSIGNMENTS, TO DANIEL SCHANZ, OF OBERSCHMITTEN, HESSE, GERMANY.

VENTILATOR FOR BUILDINGS.

Application filed July 5, 1927, Serial No. 203,325, and in Germany November 4, 1926.

This invention relates to a ventilating device for buildings of the kind composed of a frame having an outlet opening for foul air and an inlet opening for fresh air.

5 In old devices of this kind the openings are placed on the same level and close to each other, an arrangement which is not conducive to an effective change of fresh air for foul air. The object of the present invention is to improve the ventilating effect, and the invention consists in arranging the outlet opening above the inlet opening and separating the two openings by a partition which relegates to each opening its proper 10 function. The effect is enhanced by the provision of a wind shield arranged in front of the outlet opening so as to deflect the wind from the latter and convert the wind pressure into suction.

20 Means are also provided for causing sufficient outgoing air to mix with the incoming air so as to moderate the temperature of the latter, thus protecting the occupants of a room from being exposed to cold draught.

25 Fig. 1 of the accompanying drawing represents a front view of the improved ventilator according to one construction,

Fig. 2, a vertical section of the same on line 2—2 of Fig. 1,

30 Fig. 3, a front view showing parts in section to better disclose the construction of a modified arrangement,

Fig. 4, a vertical section on the line 4—4 of Fig. 1.

35 The ventilator consists of a frame *a* which is built into the wall near the ceiling and fitted with a partition *d* so as to form two superposed openings *b* and *c*, one for the discharge of the hot air which accumulates 40 under the ceiling and the other for the admission of fresh air. The outlet opening *b* is protected by a wind shield *f* which is composed of angularly assembled plates arranged so as to form two lateral channels *e* leading from above into the opening *b* and two upwardly directed outlet channels *e'*. The shield *f* deflects the wind from the opening *b* and converts the wind pressure into a suction effect whereby the foul air is drawn 45 out through the opening *b*.

50 In the structure shown, the partition *d*

which separates the two openings *b* and *c*, is curved outwards in a vertical plane and corrugated so as to form, at both sides of the partition, i. e., at the front and rear 55 thereof, vertical channels through which part of the hot air can be led back towards the opening *c* for mixing with and modifying the temperature of the incoming fresh air, the occupants of the room being thereby 60 protected from cold draught.

I claim:

1. A ventilator for buildings comprising a frame and a partition arranged in said frame so as to form two superposed openings, one for admitting and the other for discharging air, said partition being formed to provide vertical channels connecting said 65 openings.

2. The ventilator structure claimed in 70 claim 1 and a wind shield arranged in protecting position in front of the outlet opening.

3. A ventilator for buildings comprising a frame, a partition arranged in said frame 75 so as to form two superposed distanced openings, one for admitting and the other for discharging air, and a wind shield arranged in protecting position in front of the outlet opening, said partition and shield being 80 shaped so as to form channels between them to which part of the outgoing air can mix with the incoming air, substantially as and for the purpose set forth.

4. A ventilator according to claim 3 85 wherein the partition is curved outwards from one opening to the other.

5. A ventilator according to claim 3 wherein the partition is curved outwards in a vertical plane and corrugated so as to form 90 inside and outside air channels leading from one opening to the other.

6. A ventilator according to claim 3 wherein the wind shield is formed with angularly assembled planes and is arranged 95 so as to direct the outgoing air upwards and towards both sides.

7. A ventilator for buildings comprising a frame, a partition arranged in said frame so as to form two superposed openings, one 100 for admitting and the other for discharging air, and having means connecting said open-

ings for admixture of a part of the outgoing air with the incoming air.

8. A ventilator comprising a casing open at the front and rear, a partition in said casing subdividing the same to form a lower cold air inlet and an upper warm air outlet and passages connecting the same, a windshield at the upper front portion of the cas-

ing consisting of angularly related upper and lower plates forming lateral air passages communicating with the warm air outlet, and an outlet passage extending through the upper plate and communicating with the warm air passage. 10

ALEXANDER GERLACH.
